[57] CLAIM

The ornamental design for a vehicle step covering and shoe
cleaning device, as shown and described.

DESCRIPTION

FIG. 1 is a perspective view of a vehicle step covering and
shoe cleaning device showing my novel design;

FIG. 2 is a top plan view thereof;

FIG. 3 is a bottom plan view thereof;

FIG. 4 is a rear elevational view thereof;

FIG. 5 is a front elevational view thereof; and,

FIG. 6 is a right side elevational view of the vehicle step
covering and shoe cleaning device which is a mirror image
of the left plan view.

The vehicle step covering and shoe cleaning device shown
is attachable to a vehicle entrance and provides a means of
shoe cleaning before entering the vehicle.
